UNITED STATES PATENT OFFICE

2,639,943

MACHINE FOR APPLYING MATERIAL TO
WALLS

Spencer A. Earnshaw, Los Angeles, Calif.

Application April 30, 1948, Serial No. 24,338

14 Claims. (Cl. 299—63)

1

This invention relates to coating machines especially adapted for applying a coating material to walls and ceilings and other surfaces, for example the coating of pipes and coating of ditches and tunnels and other shaped articles and for filling forms.

An object of this invention is to improve the method of applying materials in the construction of structures, such as walls, retaining walls, lining or coating.

Another object of the invention is to provide a coating machine which is power driven and which includes a pair of rotary drums adjustably mounted to a frame unit which is so constructed and arranged to permit the frame to pivot and so constructed to permit the unit to be raised and lowered as desired.

Another object is to set the machine in a stationary position to coat articles or surface that come in contact with the stream of materials that is discharged from the machine.

Another object is to provide variable speeds for raising and lowering the frame unit for discharging material.

Another object is to provide means to regulate the speed of throwing a premixed material at a very high velocity.

An object of the invention is to mix the material inside the hopper.

Another object of the invention is to throw from a narrow stream to a wide stream of material and to throw a plural number of streams.

A feature of the invention is the novel construction and arrangement whereby is provided attached to the machine revolving deflector means that are adjustable and will rotate clockwise and/or counterclockwise for the purpose of changing the direction of the stream or streams of the material and to discharge said material at a desired velocity.

Another feature of the invention is that the machine is so constructed and arranged so that it may be placed on its end or in a vertical position and the hopper supplied with material through the door shown in the side of the hopper.

An advantage of the invention is that the drums or rollers are adjustably mounted and provided with motor means for individual rotation of each drum when desired by the operator.

The invention may have a variety of applications and certain of the features of construction may be embodied in a variety of structures.

Other objects, advantages and features of invention may appear from the accompanying drawings, the subjoined detailed description and the appended claims.

The accompanying drawings illustrate the invention.

Figure 1 is a side elevation of the invention omitting the hopper lid with parts broken away to show interior construction and also shows the pusher plate and cam to operate it and shows the

2

deflector roller and adjustment connected to the frame unit.

Fig. 2 is a front fragmental elevation of the machine showing the frame unit and drums mounted to the machine uprights and also shows the elevating and lowering cables and cable drums. Parts of the uprights are broken away and partly shown in section and also shows the slides mounted therein.

Fig. 3 is a fragmental front elevation in detail showing the side frame member construction and shows how the adjustable drums are mounted therein.

Fig. 3a is a fragmental enlarged detail view partly in section showing one of the adjustable clamps and construction thereto.

Fig. 4 is a plan section taken on line 4—4 Fig. 3 showing how the spacer block is constructed in the frame unit.

Fig. 5 is a detail view partly in section showing a plurality of drums fixed together on a shaft to form a roller.

Fig. 6 is a top plan view of the machine showing the driving mechanism of gears for rotating the feed screws and also shows how the hopper is fixed to the frame unit and the rotating deflector means are also shown.

Fig. 7 is a diagrammatical side elevation of the gears that drive the feed screws and the arrows indicate the direction of rotation.

Fig. 8 is a side elevational detail view of the gear shift clutch and also shows a clutch lever that may be used on some of the gears of the gear train for regulating the rotation of the feed screws.

Fig. 9 is a side elevational detail view of the worm and worm wheel drive for operating the rotation of the frame unit and hopper and also shows a fragment of the upright.

Fig. 10 is a perspective view of a larger and smaller roller having a resilient sleeve mounted thereon that may be used to replace the drums in the machine.

Fig. 10a shows a drum having horizontal treads.

Fig. 10b shows a drum having circular treads.

Fig. 11 is a side elevational view of two drums or rollers that may be filled with fluid and that are made of rubber and being resilient so that a rock may pass through as shown.

Fig. 12 is a side elevation of the machine showing parts of the uprights broken away to show the unit frame and hopper and drums and worm-wheel and worm drive connected to the motor and also shows in dotted or broken lines another position of the unit frame and hopper.

Fig. 13 is a plan-detail view of the hopper omitting the top lid and shows the partition and how it is held in place in the hopper.

Fig. 14 is a front elevation of the hopper and shows an opening through which the drums extend.

Fig. 15 is a diagrammatic view showing a

method of feeding the material at a high speed into the drums by a speeding belt having reenforced ridges or ribs for a tread. A pneumatic roller with a resilient surface to give the material the same speed as the belt is shown mounted thereon. Also shows a second roller for the purpose of giving the material the final pressure and speed as it leaves the belt. When a slower speed is required the rollers may not be used and the drums may be separated to permit material particles to pass between the drums where it is desired to feed material at lesser speeds.

Fig. 16 is a fragmental side elevational detail view of the belt construction showing reenforced ridges or ribs that enables the material to be accelerated by the belt.

Fig. 17 is a plan view of Fig. 16 showing the reenforcing ribs or ridges and how they are located thereon.

Fig. 17a is a front elevation of a pair of tire like constructed drums which may be inflated if desired and their surface will yield to pressure and grip the material and discharge the material at a high velocity. The lower drum is shown provided with a resilient sleeve that protects the surface of the drum. They may be used in single or plural units as required to accomplish the desired work.

The one sleeve shown in section shows how it will cover two of the drums. Also shows arrangement of the spaced drums so that a multiple number of streams of material may be thrown.

Fig. 18 is a diagrammatic view showing a construction and design of drum or roller units supported to a hopper and a means to feed material and discharge the material from the hopper at a high velocity. The hopper may be used in several different positions as upright or horizontal as desired and may be stationary or mounted on a truck or wheels or used in between uprights to be raised or lowered. Also shows a pipe in vertical position that may be rotated in a clockwise or counterclockwise direction while being coated with a plural number of streams of material particles.

Fig. 19 shows a modified construction diagrammatically of a section of an irrigation ditch and shows a means of throwing material at the sides and bottom of the ditch by the use of sets of drums or rollers suitably mounted to carry out this operation or operations and may be of any length to meet the different requirements.

It is understood that the coating machine may be made in different shapes and sizes and various parts of the invention may be constructed without departing from the spirit of the invention; but the form shown is at present deemed most desirable for easy and cheap construction and ready interchange of parts.

It is also understood that the frame unit 1 may be pivoted as shown in the drawings or in any position as desired to accomplish the best results as above the center, below the center, ahead of the center or to the rear of the center so as to balance and also to give the proper stream conditions in various jobs.

The invention comprises a frame unit 1 that is so constructed and arranged to be raised and lowered in the uprights 2 that may be of channel iron construction being supported by the rollers 3 mounted in the brackets 4 as shown in the drawings.

A tie member 5 is shown at the top to hold the uprights 2 in position and slide members 6 are 75

raised and lowered in the uprights 2 by the cables 7 that are mounted over the pulleys 8 and extend downward on the outside of the uprights to winding drums 9 that are operated by the motors 10 that are fixed to the uprights.

Revolvably mounted to the uprights 2 is the frame unit 1 that is fixed thereto a hopper 11 and the drums 12 and 13 are adjustably mounted to the frame unit and a worm wheel 14 and worm 15 operated through a flexible drive shaft 16 and motor 17 revolve the frame unit 1 when desired.

The frame unit 1 being pivoted on the shaft 18 that is mounted in the slide members 6, and the drums or rollers 12 and 13 revolve and are 15 mounted in the roller bearings 19 that are housed in the vertical members 20 and 21 of the frame unit.

The adjustable drums or rollers 12 and 13 are mounted in the roller bearings 19 of the housing 20a that are spaced apart by a spacer block 22 and held in place by clamps 23 that comprise adjusting screws 23a that rest against the rubber shock absorber 24 to absorb all shocks caused by any large particles of hard material as rocks 25 that may find their way between the drums.

An elongated slot 25 is shown in the vertical members 20 and 21 of the frame unit 1 that provides a means to permit adjustment for the drums 12 and 13 to allow for various types of gripping pressures, and spacer block 22 may be made in various sizes.

The drums 12 and 13 are rotated through the belt drive 26 by the motors 27 that are mounted on the top and bottom members of the frame unit 1.

Brackets 28 that form a support for the machine are fixed to the uprights 2 and extend backward to permit a swiveled roller or rollers 29 to be attached thereto and also support the motor 17.

The hopper 11 is provided with a partition 30 that supports end bearings for the feed screws 31 that are provided at their other ends with the thrust bearings 32 as shown in Fig. 6 of the drawings.

The feed screws 31 are rotated by a motor 33 which will be reversible in directional drive and that is fixed to the underside of the hopper 11 and the motor drives through a chain drive 34 to a bevel gear 35 that meshes into bevel gear 36 that is integral with a drive gear 37 that meshes into a train of drive gears 38.

A guard or shield 39 is shown fixed to the inside of the hopper that will prevent the material in the hopper from interfering with the action of the drums or rollers.

The feed screws are so arranged and constructed and are reversible in directional drive that puts the material in motion and can also retard or speed up the motion of the material and to control the material when the hopper is in different positions.

To this end I provide a clutch 40 operated by a lever 41 that may be attached to the feed screw drive gears 38.

Slidably mounted in the bottom of the hopper 11 is a pusher plate 42 that is operated through cams 43 by the chain drive 44 by a motor 45, the cams are mounted on the shaft 46 that is supported by the brackets 47 that are fixed to the hopper end. This pusher plate moves the material against the drums surfaces that receive and grip the material to be discharged.

To change the direction of the stream or streams of material as it is discharged from the

drums, I provide adjustable revolving deflector means 48 that rotate clockwise and/or counter-clockwise, and that may be used as a buffer by replacing the drums with wire brushes and the present form shown is of a resilient tread but may be of different kinds of tread or elements as the work requires.

These deflector means comprise a plurality of drums 49 that are mounted on a shaft 50 to form a roller that is rotated through a chain drive 51 to a motor 52 that is adjustably mounted on a bracket 53 on the top of the frame unit 1.

The shaft 50 is supported by an arm bracket 54 that is constructed to permit the deflector drums 49 to be raised upward or downward through a slot 55 in the bracket 56 and being held in position by the bolts 57.

Referring to Fig. 10 indicates a large roller 58 having a resilient rubber sleeve 59 and a smaller roller 60 having a resilient rubber sleeve 61 that may replace the drums 12 and 13 when the work requires it.

There is shown in Fig. 10a a drum provided with a horizontal tread 62 and in Fig. 10b a drum having a circular tread 63.

In Fig. 11, I provide a set of drums 64 of rubber that may be filled with fluid and show a valve at 65 to permit filling and regulation of the fluid.

Referring to Fig. 15, I provide a belt 66 having reinforced ribs 67 and being resilient and mounted on the belt is a resilient roller or drum 68 having a valve 69 to permit the drum to be inflated. This drum or roller will give the material the same speed as the belt and a second roller 70 that gives the material the final pressure and speed as it leaves the belt.

In Fig. 17a is shown a plurality of spaced drums 71 so that a multiple number of spaced streams of material may be thrown.

To carry out this operation a multiple number of belts of the construction shown in Fig. 15 may be used.

Referring to Fig. 18 shows a hopper 72 fixed to a frame unit 12a that supports a multiple number of drums or rollers units 73 and shows guards 74 that prevent the material in the hopper from interfering with the action of the rollers.

A lid is shown at 75 closing the top and will be removed when feeding the material to the hopper and closed when the hopper is being fed at 76 or from either of the other positions. By this arrangement a plurality of coatings may be made at one time by allowing one stream of material to pass over the surface of the other streams of materials as the machine is moved or the work is moved past the machine. The rollers may be replaced by wire brushes in this hopper.

Fig. 19 shows a ditch 77 which is of the usual general construction to be lined with materials and I show units of drums or rollers 78 so constructed and arranged to do this work by a plural number of streams.

79 shows a vertical pipe that rests on a base 80 that may be rotated clockwise or counter-clockwise by mechanism not shown and then moved away from in front of the machine.

In the present art of coating pipe, a single narrow stream is applied to the pipe's surface while the pipe revolves and said stream of material must travel the full length of the pipe, or the desired length of the coating regardless whether the pipe is moved on a track or the machine is moved on a track, but in my invention any desired number of streams of material may be thrown onto the pipe and, if the throwing ele-

ments are evenly spaced when the stream from one set of throwing elements comes to the place on the pipe where the other stream started, the coating will be complete for the full length of the pipe or the desired length of the coating.

The thickness of the coating will be determined by the travel of the machine and/or the pipe. This multiple number of streams will revolutionize the pipe coating industry and other industries. 10 Also a very wide stream of material may be thrown to accomplish the width and thickness of the coating as the pipe revolves and then the stream is stopped and the machine or pipe may be moved, then the coating will continue from 15 the stopping point.

The hopper 11 is provided with a lid 11a that is put on when the hopper may be fed with material through either side that is shown covered by the covers 11b in Fig. 12 of the drawing and the worm 15 is supported by a bracket 15b to the unit frame 1.

A plate 11c is shown in the bottom of the hopper 11 that forms a guide for the pusher plate 42.

20 Material may be fed to the hopper or drums by the use of nozzles or other means depending on the work to be done.

In Fig. 2 the slide members 6 are shown broken as they are of longer length and when the frame unit 1 is placed in a vertical position the ends of the slide members will fit into the uprights.

I claim:

1. In a machine of the character set forth having a frame unit pivotally mounted and a hopper fixed thereto; said frame unit being mounted in an upright frame and provided with slide members slidably mounted in said upright frame having means to raise and lower said frame unit; a shaft having a plurality of drums mounted thereon to form a roller; a second shaft having a plurality of drums mounted thereon to form a roller, said rollers mounted in vertical members of said first mentioned frame unit and adjustable means to close and separate said rollers; means to revolve said drums and means to feed material to said drums to be discharged therefrom.

2. In a machine for coating material comprising an upright frame mounted to be moved in any direction, a frame unit pivotally mounted to said upright frame, a hopper, fixed to said frame unit, having its front end open; drums mounted within the hopper at the front end thereof; means to revolve said drums, and means comprising feed screws and a pusher plate within the hopper to feed material to said drums to be discharged by said drums at a desired velocity.

3. A coating machine of the character set forth, comprising: a hopper, a shaft, a drum provided with a yieldable surface, mounted on said shaft; a second shaft, a drum provided with a yieldable surface mounted on said second shaft, said first shaft and said second shaft having shock absorber means adjustably mounted on a frame unit forward of said hopper so that the treads or surfaces of said drums can be squeezed against each other so that each drum surface will yield to the pressure of the other drum surface so that a holding effect can be produced on the material particles which pass between said drum surfaces, and motor means to drive said drums and slidably pusher plate means to feed material to said drums for velocity discharge.

4. A machine for applying material of the character set forth, including a hopper for the mate-

rial, parallel rotary drums within the hopper; a plural number of feed screws mounted in the hopper at the induction side of said drums, means for driving the feed screws either clockwise or counter-clockwise to mix, retard or speed up and to control the feeding of the material in said hopper between the drums to be discharged from the ejection side thereof.

5. In a machine of the character set forth for applying material, comprising: a hopper mounted in a frame unit, rotary drums mounted parallel with each other located forward of the hopper; a plurality of feed screws mounted in said hopper having means to drive said screws clockwise and/or counter-clockwise, and means to disengage from said drive means, one or more of said feed screws, so as to regulate the material discharged from the hopper and machine.

6. A machine for applying material of the character set forth, including: a pair of rotary drums having resilient surfaces, mounted to a revolvable frame unit, and means comprising a worm and worm wheel driven by a motor to revolve said frame unit, said drum surfaces adapted to yield to the pressure of material particles which are accelerated by the drums; said yielding effect being due to the resilient action of said drum surfaces that stretches and compresses around material particles forming recess-like pockets, and means to drive said drums.

7. A machine for applying particled material of the character set forth, including a drum provided with a resilient surface, a second drum providing an opposing surface to the first drum, means for rotating the second drum, and means for feeding particled material between the surfaces of the two drums, the resilient surface of the first drum maintaining particled material against the surface of the second drum to discharge the particled material at a velocity sufficient to compact the particles of said material against a surface at a distance from the machine.

8. In a machine of the character set forth comprising a frame unit which is pivotally mounted to an upright frame unit, which is mounted on wheels so as to be moved in various directions; a shaft mounted in said first mentioned frame unit and means to drive said shaft, a multiple number of drums mounted on said shaft to form a roller; a second shaft parallel with said first shaft and mounted in said first mentioned frame unit, and means to drive said second shaft; a multiple number of drums mounted on said second shaft to form a roller; a spacer block mounted at each end of the shafts for the purpose of holding the first shaft and the said second shaft a desired distance apart; the surface of the drums constructed of rubber-like material so that an elasticity action of the drum surfaces is produced against the material particles which pass between the drum surfaces; a hopper attached and mounted to the rear of said first mentioned frame unit; a multiple number of worms in said hopper which are reversible in drive and are controlled by disconnecting clutches and means to drive said worms at suitable speeds and directions to mix material and force material from the hopper; a pusher plate within the hopper functioning as a ram to force material from the hopper and to resist material from leaving the hopper and means to drive said pusher plate at various speeds; and means to adjust the height of the drums relative to the depth of the hopper so that proper feeding conditions of the material will result to eliminate the overfeeding of the drums or rollers.

9. In a machine of the character set forth comprising a frame unit which is pivotally mounted to an upright frame unit which is mounted on wheels so as to be moved in various directions; a shaft mounted in said first mentioned frame unit and means to drive said shaft, a multiple number of resilient drums mounted on said shaft to form a roller; a second shaft parallel with the first shaft and mounted in said first mentioned frame unit and means to drive said second shaft; a multiple number of resilient drums mounted on said second shaft to form a second roller; a spacer block mounted at each end of the shaft for the purpose of holding the first shaft and said second shaft the desired distance apart; a hopper attached to and mounted to the rear of said frame unit; a multiple number of worms in said hopper which are reversible in drive and are controlled by disconnecting clutches and means to drive said worms at suitable speed; a pusher plate within the hopper providing a ram to feed material from the hopper, means to drive said pusher plate; means to adjust the height of the resilient drums relative to the depth of the hopper; a pair of side plates fastened to the front sides of the first mentioned frame; an extension arm secured to each side plate, and a revolving deflector carried between the extension arms.

10. The device as set forth in claim 7, characterized in that means is provided forwardly of the first and second drums and in the path of discharge of the particled material therefrom for diverting the path of said particled material in a given direction.

11. The device as set forth in claim 7, characterized in that a rotary drum is provided, spacedly mounted forwardly of the first and second drums in the path of discharge of material therefrom for diverting the path of said particled material in a given direction.

12. The device as set forth in claim 7, characterized in that there is provided a resilient surfaced drum, means for spacedly mounting said drum forwardly of the first and second drums, for swinging movement relative to the path of discharge of the particled material between said first and second drums, for diverting said path of movement of the particled material to a selected direction.

13. The machine of claim 6 in which the resilient surface of at least one of the rotary drums is ridged to provide a series of closely spaced grooves.

14. The machine of claim 7 in which the resilient surface of at least one of the two drums is ridged to provide a series of closely spaced grooves.

SPENCER A. EARNSHAW.
